LADDER

Alexander Kostuk, Bronx, N. Y.

Application April 22, 1938, Serial No. 203,664

5 Claims. (Cl. 228—17)

This invention relates to ladders and has for the primary object the provision of a device of this character wherein uprights of the ladder may be shortened and lengthened to permit the ladder to be adjusted to desired lengths so that the ladder may be employed to reach different heights above a supporting surface and which will permit collapsing of the ladder into a very short and compact device so that it may be conveniently carried and stored in a small space.

Another object of the invention is the provision of a construction which may be built into step ladders or ordinary straight ladders.

With these and other objects in view, this invention consists in certain novel features of construction, combination and arrangement of parts to be hereinafter more fully described and claimed.

For a complete understanding of my invention, reference is to be had to the following description and accompanying drawings, in which:

Figure 1 is a front elevation illustrating a ladder constructed in accordance with my invention.

Figure 2 is a sectional view taken on line 2—2 of Figure 1.

Figure 3 is a side elevation illustrating the ladder in a collapsed and folded position.

Figure 4 is a side elevation showing the ladder adjusted for use on a stairway.

Figure 5 is a horizontal sectional view taken on line 5—5 of Figure 2.

Figure 6 is a horizontal sectional view taken on line 6—6 of Figure 2.

Figure 7 is a horizontal sectional view taken on line 7—7 of Figure 2.

Figure 8 is a sectional view taken on line 8—8 of Figure 5.

Figure 9 is an exploded perspective view illustrating the construction of the collapsible legs embodying a part of my invention.

In illustrating and describing the present invention I have elected to show a step ladder constructed in accordance with the present invention. However, it is to be understood that an ordinary straight ladder may be constructed in accordance with the present invention.

Referring in detail to the drawings, the step ladder is shown as consisting of the usual uprights 1, supporting legs 2, a rest 3 and steps 4 with a foldable shelf 5 carried by the legs 2. In the present invention the legs 2 have steps 6 similar in construction to the steps 4 on the uprights 1. However, these steps 6 may be omitted if desired. The rest 3 has the legs hinged thereon, as shown at 7, and cushion blocks 8 are se-

cured on the rests for checking the swinging movement of the legs away from the uprights when the ladder is placed in an operative position. The legs and uprights of the ladder are composed of a plurality of telescopic sections. The opposite sections of the uprights and the legs have the steps secured thereon. The sections of the uprights and legs are of channeled construction, as shown in Figure 9, each section having a slot 7' with a lip 8'. The lip 8' of each section fits or travels in the slot 7' of the adjacent section permitting the sections to be slid endwise relative to each other for a limited distance. The lips 8' operating in the slots 7' prevent entire separation of the sections. The steps 4 are provided with sleeve-like ends 9 in which the telescopic sections are received and carried by said steps are spring pressed plungers 10 adapted to enter openings 11 of the sections whereby said sections are releasably secured for sliding movement relative to each other and for securing opposed sections to a step. The spring pressed plungers include finger pieces 11' depending a slight distance below said steps so that they can be easily grasped for contracting the plungers and thereby freeing the sections for adjustment relative to each other. The steps are preferably of channel iron construction arranged in inverted position, that is, with the flanges depending downwardly protecting and partially concealing the spring pressed plungers.

It will be seen that the legs and uprights of this ladder constructed as described will permit the ladder in entirety to be adjusted to various lengths or, if desired, the legs may be adjusted to one length and the uprights adjusted to another length so that the ladder may be used on a stairway, as shown in Figure 4.

The shelf 5 is hinged onto one of the steps of the legs, as shown at 12, and has pivoted there-to braces 13 provided with beveled free ends 14 and notches 15 adjacent said ends. The step on the legs directly below and next to the step on which the shelf is hinged is provided with socket portions 16 to receive the free ends of the braces 13 for maintaining the shelf in a supporting position. However, the braces may be easily removed from the socketed elements 16 to allow folding down of the shelf and when the legs and uprights are completely collapsed, as shown in Figure 3, the notches of the braces may engage with pins 17 carried by the lowermost sections of the uprights and thereby maintain the ladder collapsed and folded.

What is claimed is:

1. A ladder comprising the combination of spaced uprights each comprising a plurality of telescopic sections, a rest connecting said uprights, legs hinged on said rest and each comprising telescopic sections, steps having sleeve-shaped ends to receive the telescopic sections of the uprights and legs, means acting to prevent complete separation of said telescopic sections of the uprights and legs, means carried by said steps 5 and engageable with said telescopic sections for securing the steps against relative movement on said sections and for securing the sections against endwise movement with relation to each other, a shelf hingedly attached to one of the steps of said legs, and braces pivoted to the shelf and engageable with a lower step when said legs are in an extended position and engageable with the said uprights when in the collapsed position for securing the same in a fully folded and collapsed position.
- 10 2. A ladder comprising the combination of spaced uprights each comprising telescopic sections, a rest connecting said uprights, legs hingedly mounted on said rest, each of said legs comprising telescopic sections, steps having sleeve-like ends receiving the telescopic sections of said uprights and legs, said sections having openings, spring pressed plungers carried by said steps and engageable in said openings to releasably secure the telescopic sections against endwise movement with relation to each other, a shelf hingedly attached to one of the steps of said legs, and braces pivoted to the shelf and engageable with a lower step when said legs are in an extended position and engageable with the said uprights when in the collapsed position for securing the same in a fully folded and collapsed position.
- 15 3. A ladder comprising the combination of spaced uprights each comprising telescopic sections, a rest connecting said uprights, legs hingedly mounted on said rest, each of said legs comprising telescopic sections having elongated slots, steps having sleeve-like ends receiving the telescopic sections of said uprights and legs, said sections having openings, spring pressed plungers carried by said steps and engageable in said openings to releasably secure the telescopic sections against endwise movement relative to each other, said sections having lips engaging in the 20 slots for slidably connecting the sections and for preventing complete separation of the sections, a shelf hingedly attached to one of the steps of said legs, and braces pivoted to the shelf and engageable with a lower step when said legs are in an extended position and engageable with the said uprights when in the collapsed position for securing the same in a fully folded and collapsed position.
- 25 4. A step ladder comprising the combination of spaced uprights each comprising telescopic sections, a rest connecting said uprights, legs hinged on said rest and each comprising telescopic sections, means for slidably connecting said sections and coacting therewith to limit endwise movement of said sections relative to each other, steps having sleeve-like ends receiving the telescopic sections of the uprights and legs, said sections having openings, spring pressed plungers carried by the steps and engageable in said openings, a shelf hingedly attached to one of the steps of said legs, and braces pivoted to the shelf and engageable with a lower step when said legs are in an extended position and engageable with the said uprights when in the collapsed position for securing the same in a fully folded and collapsed position.
- 30 5. A step ladder comprising uprights each including telescopic sections, a rest connecting said uprights, legs hinged on said rest and each including telescopic sections, means for slidably connecting said sections together and limiting the endwise movement of said sections to prevent separation of the sections, steps including sleeve-like ends to receive companion sections of the 35 uprights, steps having sleeve-like ends receiving the sections of the legs, said sections having openings, spring pressed plungers carried by the steps and engageable in said openings, cushion blocks carried by the rest for limiting hinging movement of the legs away from the uprights, a shelf hinged on said legs, braces pivoted on said shelf and engageable with one of the steps for supporting the shelf in an operative position, pins carried by the lowermost sections of the uprights, said braces having notches engageable with the pins for securing the uprights and legs in fully collapsed and folded position.
